(No Model.)

J. C. WUERFEL.

SAW MILL.

No. 272,610.

Patented Feb. 20, 1883.

UNITED STATES PATENT OFFICE.

JOHN C. WUERFEL, OF TOLEDO, OHIO.

SAW-MILL.

SPECIFICATION forming part of Letters Patent No. 272,610, dated February 20, 1883.

Application filed December 1, 1882. (No model.)

To all whom it may concern:

Be it known that I, JOHN C. WUERFEL, a citizen of the United States, residing at Toledo, in the county of Lucas and State of Ohio, have invented a new and useful Saw-Mill, of which the following is a specification, reference being had to the accompanying drawings.

This invention relates to head-blocks or carriages for saw-mills; and it consists in certain improvements in the construction of the same, which will be hereinafter fully described, and particularly pointed out in the claim.

In the drawings, Figure 1 is a perspective view of a saw-mill head-block or carriage to which my invention has been applied, and Fig. 2 is a detail view.

The same letters refer to the same parts in both figures.

In saw-mill carriages, as heretofore constructed, various kinds of mechanism have been heretofore employed to move the knees back from the saw after a log has been sawed down, in order to make room for the next log; but, so far as I am aware, this retrograde movement of the knees has always been effected after the carriage has been returned to its position in front of the saw, thus making it necessary to keep the mill out of operation while this movement was effected. Now, the object of my invention is to save the time usually consumed in moving the knees back by effecting this during the backward movement of the carriage, as I shall now proceed more fully to describe with reference to the drawings, in which—

A represents the frame of the saw-mill carriage, which is constructed in the usual manner, and adapted to slide or move upon a suitably-constructed track. Said carriage is provided with transverse guides or tracks for the knees or head-blocks B B, which are adapted to be moved by any suitable mechanism upon the said tracks in a forward direction, so as to feed the log forward to the saw.

C is a bent or bell crank lever, pivoted between the front ends or arms of a yoke, D, and having a downward-projecting arm or strap, E, pivoted upon a bolt, F, between a pair of ears or lugs, G G, upon the carriage. The rear end of the yoke D has a shaft, H, upon which is journaled a friction-wheel, I, adapted to bear against and operate another friction-wheel, J, mounted upon the shaft K of the set-wheel L. Said set-wheel engages in the usual

manner miter wheels or pinions M M upon a longitudinal shaft, N, the ends of which carry pinions O O, adapted, through any suitable intermediate mechanism, to actuate the knees. The ends of the shaft H project slightly beyond the yoke D, and are adapted to slide in slots P in a pair of straps, Q Q, which connect the ears or lugs G G with a pair of similar ears, R R, secured upon the carriage. When the lever C is manipulated the slots P guide the friction-wheel I in a rearward and downward direction until it strikes the friction-wheel J, and at the same time strikes a track or rail, S, secured upon the floor of the mill adjoining and parallel to the carriage.

The operation of my invention will be readily understood from the foregoing description, taken in connection with the drawings hereto annexed. When a log has been sawed up, and the carriage is to be returned for the purpose of taking on a new log, the sawyer or attendant depresses the lever C, thus throwing the friction-wheel I into engagement with both the friction-wheel J and the track-rail S. As, by the usual proper machinery, the carriage is returned the friction-wheel I, by contact with the track-rail, is revolved, thus revolving the friction-wheel J, which it engages, and moving the knees B B back upon the carriage, and making room for the next log. When released the lever C automatically returns to its original position.

I am aware of the patent to Russell, No. 121,664, of December 5, 1871, and I claim nothing therein shown.

I claim as my invention and desire to secure by Letters Patent of the United States—

The combination and arrangement, as described, of the saw-mill carriage, the set-wheel shaft having a friction-wheel, the yoke having a shaft sliding in suitable guide-slots, and carrying a friction-wheel adapted to engage simultaneously the friction-wheel upon the set-wheel shaft and a track-rail secured upon the floor of the mill, and a bent or bell-crank lever adapted to operate the yoke, all as herein described, for the purpose set forth.

In testimony that I claim the foregoing as my own I have hereto affixed my signature in presence of two witnesses.

JOHN CARL WUERFEL.

Witnesses:

C. J. SWAN,
C. K. ALLEN.
